UNITED STATES PATENT OFFICE.

WILLIAM SPARKS, OF JACKSON, MICHIGAN, ASSIGNOR TO THE SPARKS-WITHINGTON COMPANY, OF JACKSON, MICHIGAN, A CORPORATION OF MICHIGAN.

SIGNAL.

1,227,085.

Specification of Letters Patent. Patented May 22, 1917.

Application filed October 8, 1915. Serial No. 54,736.

To all whom it may concern:

Be it known that I, WILLIAM SPARKS, a citizen of the United States of America, and resident of Jackson, in the county of Jackson, in the State of Michigan, have invented new and useful Improvements in Signals, of which the following, taken in connection with the accompanying drawings, is a full, clear, and exact description.

10 This invention relates to certain improvements in mechanically operated signals, of the cam-actuated-diaphragm type.

The primary object of the invention relates to the production of novel and efficient means for varying the overlap of the cam projections on the wear-piece of the diaphragm for varying the extent of forced vibration of the diaphragm and the sound produced thereby.

20 Other objects and advantages will appear from the following description, taken in connection with the accompanying drawings, in which—

Figure 1 is a side elevation of the device.
25 Fig. 2 is a vertical central cross section of the same.

Fig. 3 is a view of the clutch mechanism showing the case in section.

The invention as shown comprises a suitable diaphragm —1— having its marginal portion clamped between the base —2— of an amplifier —3— and a dished case section —4— having an elongated laterally extending opening arranged substantially centrally of the diaphragm, through which opening a portion of a rotary actuator —5— is adapted to project for allowing contact of the teeth —6— thereof with a wear-piece rigidly mounted on the diaphragm.

40 The actuator —5— has a toothed portion —6— positioned substantially diametrically of the diaphragm and a second portion —7— offset from the portion —6— to form a central recess —8—. The offset portion —7— of the actuator —5— is rigidly mounted upon a rotary shaft —9— having a spirally arranged portion —10— upon which is mounted a suitable actuating and clutch mechanism comprising a case —11— inclosing a nut —12— having a central opening adapted to fit the shaft —10— so that longitudinal movement of the nut —12— along the shaft —10— will cause rotation of either the shaft or the nut.

50 The case —11— is of somewhat greater

depth that the thickness of the nut —12— and is provided with projections —13— for engagement with ratchet teeth —14— formed upon the adjacent surface of the nut. As the case —11— is moved downwardly by a suitable hand-operated lever —15— the projections —13— are brought into engagement with the teeth —14— preventing rotation of the nut —12—, thereby forcing rotation of the shaft —10— and actuator —5—.

60 The operating handle —15— is adapted to be returned to starting position after each operation by a suitable spring —16—, and upon the return movement of case —11— the projections —13— are moved out of engagement with the teeth —14— allowing the nut —12— to rotate within the case, thereby allowing the return of the case —11— and nut —12— to starting position without causing rotation of the shaft —10—.

65 The ends of the shaft —10— are preferably of substantially conical shape and one of the same, as —17—, is journaled in a suitable bearing —18— adjustable through the case —19— and provided with suitable locking nuts —20— and —21— for holding the bearing in desired position. The opposite end —22— of the shaft —10— is journaled in a bearing formed upon a bar —23— positioned within the case —19— and having one of its ends, as —24—, flanged upwardly and slotted for the reception of the neck portion —25— of a thumb screw —26— having a threaded relation with and adjustable through the case —19—. The opposite end 70 of the bar —23— is provided with an elongated slot —27— in which is seated a screw or bolt —28— mounted in the case —19— and having its free end within the case provided with a nut —30— and pin —31—.

75 The nut —30— may be loosened or tightened by turning the screw —28— from the outside of the case, and, when in loosened condition, the bar —23— as a whole may be moved longitudinally of case —19— by 80 means of set screw —26—, as limited by the slot —27—. This movement of bar —23— moves the end of the shaft —9— toward and from the diaphragm —1— as desired, thereby varying the degree of overlap of the teeth of the actuator —5— upon the diaphragm wear-piece. The entire adjustment may be accomplished from the outside of the case.

85 The operating handle, the clutch and ac- 116

tuating mechanism, the shaft and actuator, the case section, diaphragm and resonator, are similar in construction to those disclosed in my co-pending application Serial No. 5 800,955.

Although I have shown and described one particular structure for accomplishing the objects of this invention, I do not desire to limit myself to any particular construction, 10 form or arrangement, as many changes may be made in the same without departing from the spirit of this invention as set forth in the appended claims.

What I claim is:—

15 1. In a signal, a case, a bar within and extending longitudinally of the case, one of said members provided with a slot, the other member carrying a bolt seated in said slot, a shaft having a bearing in said bar, and

an adjusting member engaged with the case 20 and interlocked with said bar.

2. In a signal, a casing, a shaft having bearings within the casing, one of said bearings formed in a bar having an elongated slot, a bolt engaged with the casing 25 and having a portion extending through said slot, means adjustable on the bolt for holding the bar in any predetermined position with respect to the bolt, and means operable exteriorly of the casing and adjustable 30 through the casing for moving said bar with respect to said bolt.

In witness whereof I have hereunto set my hand this 27th day of September, 1915.

WILLIAM SPARKS.
